(57) CLAIM

The ornamental design for a wall covering as shown and described.

DESCRIPTION

FIG. 1 depicts a front view of a wall covering showing my new design.

FIG. 2 depicts a bottom view thereof.

FIG. 3 depicts a top view thereof.

FIG. 4 depicts a right side view thereof.

FIG. 5 depicts a left side view thereof.

FIG. 6 depicts a back view thereof.

FIG. 7 depicts a first perspective view thereof; and,

FIG. 8 depicts a second perspective view thereof.

The long-short dash lines depict boundaries of the claim and do not form any part of the claim. The even dash lines depict portions of the wall covering forming no part of the claim.

1 Claim, 6 Drawing Sheets
